CONVERTIBLE FOLDER AND MANUSCRIPT COVER

Ervin G. Johnson, Eureka, Calif., assignor of one-half to Orville C. Whisman, Oakland, Calif.

Application April 25, 1946, Serial No. 664,860

5 Claims. (Cl. 129—16.7)

1

This invention relates to a combined letter filing folder and potential manuscript cover and has particular regard to the provision of a low cost folder and/or cover having special features of utility.

This application is a continuation in part as to each of my copending applications: Ser. No. 357,331 filed September 18, 1940; Ser. No. 399,574 filed June 24, 1941 now abandoned; which are made a part of this application.

One of the principal objects of this invention is to provide in a filing folder for fasteners which are made of the material of the folder itself; so that prior to use as fasteners they form a part of the folder itself and are only potentially fasteners, but that they may easily be placed in condition for fastening service by the application of a pencil or the like.

Another of the principal objects of this invention is to so provide in a convertible folder having fasteners therein both entirely formed from a single sheet of material, that manuscripts prepared of sheets of paper having identical size and identical looseleaf punchings, but wherein some sheets show, for example, drawings and other sheets provide text material only, are separately bound so that any sheet of drawing may be laid out flat alongside any sheet of the text material. In this way even though the same sheet of drawing may be referred to on several sheets of the text, it is available without turning over sheets of text material to refer to the one sheet of drawing. Likewise, when several sheets of drawing are referred to on the same page of text, the drawing sheets may be successively turned over without losing the desired relation of the text material.

Other objects and advantages of the invention will become apparent upon consideration of the following specification in which reference is made to the accompanying drawing, wherein:

Figure 1 is a plan view of the convertible folder and manuscript cover;

Figure 2 illustrates the manner or method of converting the folder to a manuscript cover;

Figure 3 shows the condition of the fastener as it passes through the hole of a loose-leaf sheet of manuscript paper;

Figure 4 is an enlarged fragmentary view of a potential fastener prior to breaking out for use;

Figure 5 is a similar view showing the punched paper engaged by the fastener; and

Figures 6 and 7 illustrated the use of the invention for manuscripts having drawing sheets and text sheets.

2

The convertible folder and manuscript cover is formed of a sheet of tough paper having rounded corners and a central hinge-forming score line 2 dividing the front cover portion 4 from the back cover portion 6.

The back cover portion 6 has potential fasteners 8 formed therein to, when completed, securely receive sheets of paper 36 and 38 having punched round holes 10 and 12 therein.

10 The potential fasteners 8 are formed by two parallel straight slits 14 cut entirely through the sheet 6 as shown in Figure 4, one terminus of each slit 14 being at a fastener-hinge-line 16 parallel to the cover hinge-line 2 to form the fastener anchor to the back cover portion 6 and the other terminus of each slit being disposed inwardly of the periphery of the circle formed by arcuate slits 18 which form the head 20 of the potential fastener. The arcuate slits 18 are separated from each other and the straight slits 14 by uncut portions of the sheet material at 22 and 24 which are of sufficient section only, and so arranged, that the potential fastener cannot readily be snagged and broken out prior to intentional rupture of the uncut portions 22 and 24. Diagonal scorelines 26 are provided to facilitate folding the fastener head 20 into a shape as shown in Figure 3 so that it will pass freely through the openings 10 or 12.

20 Accordingly, as long as bonds 22 and 24 are unbroken, the elements 4 and 6 form a common type of letter folder for use in offices and in which loose leaves of paper may be filed without being fouled by the potential fasteners.

30 The potential fasteners 8 are readily converted to complete usable fasteners in the mode illustrated in Figure 3. The folder is laid out flat with the inside down on a desk top and the eraser 28 of a pencil 30 is applied to the center of head 20 and held against the desk by the hand. The other hand then lifts the back portion 6 from the desk to a position similar to that shown, which causes the fastener 8' to break out on the inward side of the cover.

40 35 Pre-punched loose-leaves 36 and 38 are secured to the fasteners by first folding the wing portions 32 to a position as in Figure 3 and passing the head through the holes 10 (or 12). The holes 10 and 12 are only slightly larger in diameter than 45 the normal distance between slits 14 and are substantially smaller in diameter than the head 20. After passage of folded head 20 through the hole 10, the punched sheet is drawn rightward (as in Figure 5) so that the edge of the hole 10 50 passes under the hook portions 34 of the head

20 as shown. This flattens the wing portions 32 of the head into a common plane above and in contact with the sheet. When the front cover portion 4 is folded down against back cover portion 6, the head 20 is held flat thereby.

It will be appreciated that the thickness of the manuscript cover is more than the folder only by the thickness of the head 20 so that filing cabinet space is not substantially increased in order to maintain filed papers in the orderly manner resulting from their binding together.

In order to provide for the easy handling, reading, and comprehension of manuscripts illustrated by drawings, and at the same time use identically sized and punched sheets, potential fasteners 8' are provided at the top of portion 6 for fastening manuscript sheets by holes 12 and potential fasteners 8'' are provided along the hinge-line 16 for fastening of sheets along their right edges by holes 10 as shown in Figures 6 and 7.

The relative arrangement is as shown, that is, so that the top edges of the sheets 36 lie below the hinge line of fasteners 8' and the left edges of sheets 38 lie to the right of the hinge lines of fasteners 8''. In Figure 1 the relationship of the groups of sheets 36 and 38 is illustrated when not in use, for reading. Figures 6 and 7 show their relationship when in use for reading and demonstrate that several sheets of drawing may successively be disposed opposite a particular page of text to facilitate their consideration.

Having described my invention according to the statutes, I claim:

1. In an article of sheet material forming a letter file folder convertible to a manuscript cover having a front cover portion and a back cover portion and having a straight scored portion forming a cover hinge, a plurality of potential fasteners formed in said back cover portion, the potential fasteners being each rendered potential but not yet usable by a pair of identical straight parallel slits entirely through the sheet material forming a fastener shank portion normal to and terminating along a hinge line adjacent the cover hinge and a plurality of arcuate slits forming a ring of displaced slits centered adjacent the ends of said straight slits remote from the cover hinge, the ends of the various arcuate slits being separated by uncut portions of sheet material and the ends of the arcuate slits nearest the shank slits being separated from the latter slits by uncut portions of sheet material.

2. In an article according to claim 1, there being a plurality of said potential fasteners disposed along the cover hinge, and a plurality of said potential fasteners disposed along the top edge of the back cover portion, the fasteners being so arranged that identical sheets of punched paper may be fastened to either the first or the second group of said fasteners and that leaves fastened to each group may be interleaved.

3. In an article of sheet material forming a

letter file folder convertible to a manuscript cover having a front cover portion and a back cover portion and having a straight scored portion forming a cover hinge, a plurality of potential fasteners formed in said back cover portion, the potential fasteners being each rendered potential but not yet usable by a pair of identical straight parallel slits entirely through the sheet material forming fastener shank portions normal to and terminating along a hinge line common to two or more of said fasteners and a plurality of arcuate slits forming a ring of displaced slits centered adjacent the other ends of said straight slits, the ends of the various arcuate slits being separated by uncut portions of sheet material and the ends of the arcuate slits nearest the shank slits being separated from the shank slits by uncut portions of the sheet material.

4. In an article of sheet material forming a letter file folder convertible to a manuscript cover having a front cover portion and a back cover portion and having a straight scored portion forming a cover hinge, a plurality of potential fasteners formed in said cover, the potential fasteners each being formed, and rendered potential but not yet usable, by slits entirely through the sheet material forming fastener shank portions normal to and terminating along a hinge line common to two or more of said fasteners and a plurality of slits forming an enlarged head of greater cross dimension than the shank centered adjacent the other ends of said shank slits, the ends of the various head forming slits being separated by uncut portions of sheet material and the ends of the head forming slits nearest the shank slits being separated from the shank slits by uncut portions of the sheet material.

5. In an article of sheet material forming a letter file folder convertible to a manuscript cover having a front cover portion and a back cover portion and having a straight scored portion forming a cover hinge, a plurality of fasteners formed in said cover, the fasteners being formed by pairs of straight slits entirely through the sheet material forming fastener shank portions normal to and terminating along a hinge line common to two or more of said fasteners and additional slits forming heads for said shanks of greater size than said shanks centered adjacent the other ends of said straight slits, the slits being interrupted by portions of uncut material easily broken away.
